UNITED STATES PATENT OFFICE.

JAMES C. SNELL, OF OAK PARK, ILLINOIS, ASSIGNOR TO PREMIER ELECTRIC COMPANY, OF CHICAGO, ILLINOIS, A CORPORATION OF ILLINOIS.

RHEOSTAT.

Application filed May 2, 1925. Serial No. 27,399.

The invention relates to rheostats.

One of the objects of the invention is to provide an improved rheostat which is composed mainly of stampings, so that it can be produced at a low cost and in large quantities. Another object of the invention is to provide an improved construction in which provision is made for preventing looseness in the shaft or stud for operating the contact arm across the windings. Another object of the invention is to provide an improved rheostat which is simple in construction and efficient in operation.

The invention consists in the several novel features hereinafter set forth and more particularly defined by claims at the conclusion hereof.

In the drawings: Fig. 1 is a front elevation of a device embodying the invention. Fig. 2 is an end elevation. Fig. 3 is a vertical section. Fig. 4 is a horizontal section on an enlarged scale. Fig. 5 is a detail of the resistance element, the plate on which it is wound and the conductor terminals connected thereto. Fig. 6 is a section on line 6—6 of Fig. 5. Fig. 7 is a diagrammatic view of the parts, shown separated for the purpose of illustration.

The rheostat comprises an approximately rectangular plate 8 of insulating material which serves as a core for the resistance element; a coil of wire 9 which is tightly coiled around the core plate 8 and constitutes the resistance element; a terminal strip 10 adjacent and conforming to one end of the margin and against one face of the plate 8, and to which one terminal of the resistance wire 9 is connected; a plate of insulation 11, substantially conforming in outline to the plate 8 and extending over the back of the windings of the coil 9 and against the end margins of the back of plate 8; a terminal strip 12 conforming substantially to the end margin of the plate 8 opposite to that on which the strip 10 is disposed, fitting against the corresponding marginal portion of insulating plate 11 and to which the other terminal of the resistance coil 9 is electrically connected; an insulating plate 13, conforming in outline substantially to the plate 8 and fitting against the front of the coil 9, one margin of the plate 8 and against the strip 10; a back plate 14, conforming in outline substantially to the core plate 8 and fitting

against the back face of insulating plate 11 and terminal strip 12; a front plate 15 also conforming substantially in outline to the core plate and the back plate 14; plates 14 and 15 being formed with indented ribs or beads 33 to stiffen them transversely; an arched or forwardly bowed bearing bracket comprising an integral hub 16, diagonal arms 17 and perforated lugs 18 which extend to and lap the corners of the front plate 15. Rivets 19 extend through the corners of the plates 15, 13, 8, 11 and 14 and also through the terminal strips 10 and 12 respectively to firmly secure all of these parts in connected and operative relation. Plates 14, 15 and strips 10 and 12 are of sheet metal and may be readily and cheaply produced by punch-press work. Plates 8, 11 and 13 are also formed of sheet insulation, so that they may be readily produced by cutting and punching and at a low cost. The bracket is also formed of a plate of sheet metal. This construction thus exemplifies one in which the core, insulating plates and the supporting or frame members are all adapted to be produced by punch-press work and to be properly secured together by rivets extending through all of said parts. The hub 18 of the front bracket plate has an inturned portion 20 which is screw-threaded to receive a correspondingly threaded sleeve 29 which forms a bearing for a shaft 21. This sleeve 29 is adapted to clamp the bracket to a supporting panel 22.

A contact arm 23 of suitably resilient material has its hub riveted, as at 24, to the inner end of shaft 21, and has a backwardly turned terminal 25 which extends through an arcuate slot 26 in the front plate 15 and insulating plate 13, and is adapted to contact with the coils of the resistance element to include more or less of them in the circuit. Arm 23 is bowed forwardly and is provided with arms 27 and 28 extending oppositely from the arm to engage the front face of plate 15 to resiliently press the shaft 21 forwardly. A conoidal disk 30 has its constricted end riveted at 24 to the rear end of shaft 21 and its enlarged end adapted to engage the back face of the hub 18 of the supporting bracket. The oppositely extending spring arms function to press the shaft forwardly so the outer margin of the disk will

bear against the rear face of hub 18 and keep the shaft parallel with the axis and its bearing, to prevent it from being cramped in sleeve 29. As a result, the shaft will be automatically kept in alignment in its bearing and at right angles to the panel, so the dial or operating knob, which is usually secured to the front end of the shaft, will clear the front face of the panel. These arms also cause the pressure to be exerted upon the shaft in true axial direction, so that the shaft will be freely operable and will not rattle. This spring pressure insures contact between the contact arm and the core and between the arms 27 and 28 and the front plate 13, which are included in the circuit. These arms also insure a secondary path for current through arm 23, disk 30 and the supporting bracket. The inner end of sleeve 29 and inturned flange 20 extend into disk 30, so that the rheostat may be supported from panels 22 of different thickness without having the front end of the sleeve project varying distances from the front of the panel.

In operation, the circuit will be as follows: Terminal strip 10, resistance coil 9, arm 23, arms 27, plate 13, rivets 19 and back-plate 14 and terminal strip 12, the resistance included in the circuit depending upon the position of the arm 23 which may be turned to include any number of the coils in the circuit to vary the resistance as desired. When the arm is at the right-hand side and in engagement with the terminal strip 10, the resistance coil will be short circuited. When arm 23 is in engagement with the insulation at the left-hand margin, the circuit through the resistance coil will be open.

The invention exemplifies a rheostat which may be formed essentially of stampings of metal and insulating material; also a rheostat in which provision is made for preventing play or looseness in the operation of the shaft for rotating the contact arm by means of a resilient contact element and furthermore, the construction results in a floating shaft, which is self-aligning. In these devices, it is frequently inconvenient to provide a comparatively long bearing for the shaft, and by means of the construction described, a short bearing suffices to properly hold the shaft in use. The device is simple in construction and efficient in operation.

The invention is not to be understood as restricted to the details set forth, since these may be modified within the scope of the appended claims, without departing from the spirit and scope of the invention.

Having thus described the invention, what I claim as new and desire to secure by Letters Patent, is:

1. In a rheostat, the combination of a substantially flat rectangular core plate, a resistance element wound around said plate

to form a rectangular flat faced coil, terminal strips connected to the resistance element, a supporting bracket secured to the plate, a shaft carried by said bracket, and a wiper carried on the shaft to contact with the resistance element on a flat face thereof. 70

2. In a rheostat, the combination of a substantially flat rectangular core plate, a resistance element wound around said plate to form a rectangular flat faced coil, insulating plates against the resistance element and cover-plates having margins conforming substantially to the core plate, a supporting bracket secured to the plates, a shaft carried by said bracket, and a wiper carried on the shaft to contact with the resistance element on a flat face thereof. 75 80

3. In a rheostat, the combination of a substantially flat rectangular core plate, a resistance element wound around said plate to form a rectangular flat faced coil, insulating plates against the resistance element, and cover plates having margins conforming substantially to the core plate, an arched supporting bracket secured to the plates, a shaft carried by said bracket, and a wiper carried on the shaft to contact with the resistance element on a flat face thereof. 85 90

4. In a rheostat, the combination of a substantially flat rectangular core plate, a resistance element wound around said plate, insulating plates against the resistance elements, and frame-plates having margins conforming substantially to the core plate, terminal strips connected to the element and disposed along opposite margins of the plates, an arched supporting bracket secured to the cover plates, a shaft carried by said bracket, and means on the shaft to contact with the element. 95 100

5. In a rheostat, the combination of a core, a resistance element wound around the core, a supporting bracket for the core, a shaft slidably mounted in the bracket provided with a resilient contact arm for wiping over the element and oppositely arranged resilient arms all acting to press the shaft toward the bracket, and a stop collar on the shaft engaging the bracket under pressure of said arms. 110 115

6. In a rheostat, the combination of a core, a resistance element wound around the core, a supporting bracket for the core, a shaft rotatable and slidably in the bracket, a shaft operated contact for engaging the resistance element, a cupped disk fixed to the shaft engaging the bracket to limit the movement of the shaft in the bracket, and a threaded shaft supporting sleeve in the bracket for clamping the rheostat to panels of different thickness and extending into the cupped disk. 120 125

7. In a rheostat, the combination of a core, a resistance element wound around the core, a supporting bracket for the core, a shaft ro- 130 135

tatable and slidable in the bracket, a resilient arm having a terminal for engaging the resistance element, and an oppositely extending resilient arm on the shaft, and a conoidal disk fixed to the shaft and having its outer margin engaging the bracket.

8. In a rheostat, the combination of a core, a resistance element wound around the core, a metallic plate secured to and insulated 10 from the core, a supporting bracket for the plate and core, the bracket being provided with an inwardly extending screw-threaded flange, a sleeve adapted to extend through a panel from the front thereof and threaded 15 to said flange to clamp the bracket to a panel and provided with means at its front end whereby it may be turned, a shaft mounted in the sleeve, and a contact arm carried upon

the end of the shaft between the sleeve and element to engage the turns of the latter. 20

9. In a rheostat, the combination of a core, a resistance element wound around the core, a supporting bracket for the core, a shaft rotatable and slidable in the bracket, a resilient arm having a terminal for engaging 25 the resistance element, a conoidal disk secured to the shaft and having its outer margin engaging the bracket, and a sleeve adapted to extend through a panel, provided at its front end with means whereby it may 30 be turned and having its inner end screw-threaded to the bracket and extending into the conoidal disk.

Signed at Chicago, Illinois, this 20th day of April, 1925.

JAMES C. SNELL.
